UNITED STATES PATENT OFFICE.

RICHARD SMITH, OF PHILADELPHIA, PENNSYLVANIA, ASSIGNOR TO MAC-KELLAR, SMITHS & JORDAN, OF SAME PLACE.

DESIGN FOR PRINTING-TYPES.

Specification forming part of Design No. 6,769, dated July 8, 1873; application filed June 16, 1873.

To all whom it may concern:

Be it known that I, RICHARD SMITH, (assignor to MAC-KELLAR, SMITHS & JORDAN,) of the city and county of Philadelphia, Pennsylvania, have originated and produced a new and original Design for Printing-Type, of which the following is a specification:

The nature of my design is fully illustrated in the accompanying typographic impression, to which reference is made.

Having now set forth my invention, what I claim as new is—
The design for printing-type, as shown.

RICHARD SMITH.

In presence of—
C. F. HUCH,
GEO. WM. WITHAM.
